CONTROL APPARATUS FOR A STRIP WINDING DEVICE

William D. King, East Aurora, N.Y., assignor to Westinghouse Electric Corporation, East Pittsburgh, Pa., a corporation of Pennsylvania

Filed Aug. 30, 1957, Ser. No. 681,248
8 Claims. (Cl. 242—75.51)

The present invention relates, in general, to control apparatus for a strip winding or coiling device, and more particularly to control apparatus for controlling the tension of a strip relative to a strip winding device in a predetermined manner relative to the build-up or effective diameter of the strip on the winding device.

It is an object of the present invention to provide an improved strip winding control apparatus operative to control the tension of a strip relative to a winding reel that is operative with said strip and to provide any desired changes in the strip tension as a function of the build-up or effective diameter of the strip on the winding reel.

It is another object of the present invention to provide an improved control apparatus for a strip winding reel or device, wherein the tension of the strip relative to the winding device is varied in a predetermined manner as a function of the operating speed of the winding device and/or the movement speed of the strip.

It is a different object of the present invention to provide improved apparatus for controlling the operation of a strip winding reel, wherein the strip tension relative to the winding reel is varied as a predetermined function of the operating speed of the winding reel and/or a predetermined function of the movement speed of the strip relative to the winding reel.

It is an additional object of the present invention to provide an improved control apparatus for a strip winding or coiling device, wherein the tension of the strip relative to said device is tapered or varied in a predetermined manner and in accordance with a predetermined function of the operating speed of said winding device and/or the movement speed of said strip relative to said device.

It is still another object of the present invention to provide improved control apparatus for a strip coil winding device, which apparatus is operative to vary the tension of the strip relative to the winding device to provide a predetermined percentage change in the regulated strip tension relative to the winding device as a function of the strip build-up or effective diameter on the winding device.

These and other objects and advantages of the present invention will become apparent in view of the following description taken in conjunction with the drawings, wherein:

FIGURE 1 is a schematic showing of control apparatus in accordance with the present invention;

FIG. 2 is a curve chart illustrating the operation of the present control apparatus; and

FIG. 3 shows a schematic for the regulated D.C. voltage source shown in FIGURE 1.

In FIG. 1 there is shown a strip of material 10 movable from an entry reel 12 through a strip tension controlling device 14 and a strip coating or treating device 16, and through a first pair of strip speed controlling bridle rolls 18 and a second pair of speed controlling bridle rolls 20 between which a loop is provided in the strip, and finally the strip is supplied to a windup or delivery reel 22. A control motor 24 is operatively connected for controlling the operating speed of the delivery reel 22. A first pilot generator 26 is operatively connected to the delivery reel 22 and provides an output control signal

2

having a value proportional to the operating speed of the delivery reel 22. A second pilot generator 28 is operatively connected to one pair of bridle rollers 18 for providing a control signal having a value proportional to the operating speed of the bridle rollers 18 which, in turn, is proportional to the movement speed of the strip 10. A first fixed impedance member 30 and a first adjustable impedance member 32 are serially connected relative to the pilot generator 26. A second fixed impedance member 34 and a second adjustable impedance member 36 are serially connected relative to the pilot generator 28. The adjustable impedance member 32 is provided with a contact arm 38 which is connected through an impedance member 40 and a first pattern control winding 42 of a magnetic amplifier control device 44 to the adjustable contact arm 46 of the second adjustable impedance member 36.

The magnetic amplifier device 44 is provided with a bias winding 48 connected between suitable regulated constant potential direct current supply terminals 50 and 52. A well-known IR compensating winding 54 is connected across an impedance member 56 connected in the armature circuit of the winding reel motor 24. A voltage control winding 58 is connected to be excited in accordance with the voltage applied across the armature of the reel motor 24. The output or load windings 60 and 62 of the magnetic amplifier control device 44 are connected through suitable rectifier devices and a conventional bridge circuit 64 across an alternating current voltage supply 65 such that the field winding 66 of the reel motor 24 is energized by the output of the load windings 60 and 62.

The contact arms 38 and 46 are commonly connected to be adjusted in position by a strip tension control member 68, which is adjustable in position to provide an adjustable or tapered strip tension between 0 and 50% as may be desired and as will be later described. In this regard, other suitable percentages of tension adjustment may be accomplished with the subject control apparatus as will be readily apparent to persons skilled in this art.

The curve chart shown in FIG. 2 illustrates the taper tension control available with the adjustable impedance members 32 and 36 and the degrees of tension taper that can be obtained by the adjustment of these impedance members. The initial tension value or percent of rated tension can be set by adjusting the tension adjustment rheostat 70 within the direct current voltage source 71 shown in FIG. 3.

The curve 72 illustrates the operation of the winding or delivery reel 22 with 100% initial tension and a 0% taper or variation of said tension. The curve 74 illustrates the operation of the delivery reel 22 for 100% initial strip tension and 25% taper or variation in said strip tension. The curve 76 illustrates the operation of the delivery reel 22 for 100% initial strip tension and 50% taper or variation in said tension. The curve 78 illustrates the operation of the delivery reel 22 for 50% initial strip tension and 0% taper or variation in said strip tension, and the curve 80 illustrates the operation of the delivery reel 22 for 50% initial strip tension and 50% taper or variation in said strip tension.

In FIG. 3 there is shown a circuit schematic for the well-known regulated direct current voltage source 71 shown in FIG. 1. It is operative as a constant current device with the generator 100 having its field winding 102 controlled by the output from the load windings 104 and 106 of a magnetic amplifier device 108, having a motor armature current responsive winding 110, and a pattern winding 112 connected through a strip tension adjustment member 70 between a pair of direct current voltage supply terminals 114 and 116.

In the operation of the control apparatus shown in FIG. 1, the desired taper or variation of the strip tension relative to the winding or delivery reel 22 is provided to give an adjustable percentage decrease or change in the regulated strip tension imposed on the strip by the delivery reel 22 as the strip coil builds up to a maximum outside diameter. The initial value of strip tension imposed on the first few wraps of the strip coil on the delivery reel 22 can be adjusted by the adjustable impedance member 70 in accordance with a predetermined desired value, such as, for example only and not limitation, 100% for the curves 72, 74 and 76 as shown in FIG. 2 and 50% in accordance with the curves 78 and 80 as shown in FIG. 2. By suitable adjustment of the taper control member 68, the percentage of taper or variation in the regulated value of strip tension by which the initial strip tension as determined by the setting of the impedance member 70 is reduced when the strip coil reaches its maximum outside diameter is controlled by varying the position of the contact arm 38 on the impedance member 32 and the contact arm 46 on the impedance member 36. In this regard, the amount of taper or variation in the strip tension relative to the delivery reel 22 can be adjusted to any value between zero for which the strip tension would remain approximately constant throughout the coil build-up and 50% for which the strip tension at maximum build-up would be in the order of one-half the initial strip tension.

In this regard, greater amounts of taper or variation of the strip tension, for example, 75% may be provided by suitably determining the value of the impedance member 32 relative to the impedance member 30 and the impedance member 36 relative to the impedance member 34 as will be later explained.

The strip tension is regulated by regulating the input power to the reel motor 24 to be proportional to the strip speed and the value of the desired strip tension.

Since the various mechanical electrical winding and transmission losses of the motor, gearing and reel are not constant as the speed changes, some variation in strip tension will result as the coil builds up and as the strip speed is varied. However, these normally are small in magnitude because the change in strip tension is only a part of the total drive losses.

The taper or reduction in the strip tension as a function of the strip coil build-up on the delivery reel 22 is effected by the subject control apparatus by decreasing the counter electromotive force voltage of the reel motor 24 as the coil builds up. This is regulated by the motor field regulator which regulates the counter E.M.F. to be proportional to the strip speed minus the desired taper or variation in the strip tension.

The subject control apparatus automatically reduces the strip tension relative to the delivery reel 22. As the strip coil builds up on the delivery reel 22, the amount of reduction or taper in the strip tension from the start of the coil on the empty delivery reel 22 until the strip coil reaches its maximum rated diameter on the delivery reel 22 is adjustable by the tension control arm 68. The curve chart shown in FIG. 2 is illustrative of the operation with a delivery reel 22 having an empty delivery reel diameter in the order of 16 inches and a maximum rated strip coil build-up diameter in the order of 54 inches. Further, the curves 76 and 80 are illustrative of a reduction in strip tension in the order of 50% relative to the initial tension; however, lesser or greater percentages may be readily effected by the control apparatus in accordance with the present invention and as shown in FIG. 1.

In the operation of the control apparatus as shown in FIG. 1, power is supplied to the winding reel motor 24 from a suitable voltage source 71, including an adjustable impedance member 70 as shown in FIG. 3, such that the voltage supplied to the reel motor 24 is that necessary to circulate a regulated and adjustable amount of current

through the armature of the reel motor 24. The quantity of current sent through the armature of the reel motor 24 is set by the adjustable impedance member 70 to be proportional to the value of an initial strip tension desired, that is the tension for the first few wraps on the delivery reel 22. With the taper tension rheostat members 32 and 36 set for 0% taper by the tension control member 68, the strip tension will be held substantially constant throughout the strip coil build-up with the current regulator on the power supply and a motor counter E.M.F. regulator controlling the winding reel motor field. In this regard, the pattern field 42 of the counter E.M.F. regulating magnetic amplifier control device 44 is excited directly across the bridle pilot generator 28, the output of which is proportional to strip speed. The voltage control winding 58 is excited from the reel motor armature circuit, and the IR winding 54 is excited proportional to the armature current of the reel motor 24, with the relative strength of the latter two fields being adjusted such that in combination they supply ampere turns proportional to the reel motor counter E.M.F. Self-energizing and anti-hunt windings have not been provided on the magnetic amplifier control device 44; however, they may be included in the manner well-known to persons skilled in this particular art.

The adjustable impedance member 73 is initially adjusted to supply minimum excitation to the field winding 66 of the reel motor 24, and the output rectifiers in series with the respective load windings 60 and 62 of the magnetic amplifier control device 44 are connected such that they operate to increase the excitation of the field winding 66.

With the taper tension adjusting control arm 68 set for 50% taper, the pattern field 42 is excited from a portion of the output voltage of the bridle pilot generator 28 and a portion of the output voltage from the reel pilot generator 26. The reel pilot generator is driven directly from the delivery reel 22 such that it provides a voltage output proportional to the operating speed of the delivery reel 22. Similarly, the pilot generator 28 is operative with the bridle rollers 18 to provide an output voltage proportional to the operating speed of the bridle rollers 18 and thereby the movement speed of the strip 10. The respective output voltages of the pilot generators 26 and 28 should be initially adjusted such that they are equal at rated line feet per minute and with the delivery reel 22 turning at a speed so that its mandrel peripheral velocity is substantially equal to said line speed. The impedance members 30 and 34 and the potentiometers 32 and 36 must be so selected that the excitation supplied to the pattern winding 42 at the start of the coil build-up is the same as if the taper tension rheostat had been set at zero, and must further be such that when the coil reaches its maximum diameter, the excitation has been reduced in accordance with the setting of the taper tension control member 68.

Assuming the value of the impedance member 40 in series with the pattern winding 42 to be greater than the values of the impedance members 30 and 34 and the potentiometers 32 and 36, then the following formulas illustrate the manner of determining the value of the impedance members 30 and 34 and potentiometers 32 and 36. If E equals the voltage of the bridle pilot generator 28 at full speed and the output voltage of the reel pilot generator 26 at empty delivery reel speed, and the constant K is the ratio of the maximum coil diameter to the minimum coil diameter or the external diameter of the delivery reel 22, when the taper control member 68 is set at 50% tension taper and at the start of the coil, the following relationship is true:

$$E = \frac{R_{32}}{R_{32} + R_{30}} E + \frac{R_{34}}{R_{36} + R_{34}} E E = \frac{R_{32}}{R_{32} + R_{30}} E + \frac{R_{36}}{R_{36} + R_{34}} E$$

At maximum coil diameter the following relationship is true:

$$\frac{E}{2} = \frac{R_{32}}{R_{32} + R_{30}} \frac{E}{K} + \frac{R_{34}}{R_{36} + R_{34}} \frac{E}{2} = \frac{R_{32}}{R_{32} + R_{30}} \frac{E}{K} + \frac{R_{36}}{R_{36} + R_{34}} E$$

If we subtract Equation 2 from Equation 1 and reorganize the following is true:

$$\frac{R_{32}}{R_{32} + R_{30}} = 1/2 \times \frac{K}{K-1}$$

Further, it can be shown that the quantity

$$\frac{R_{36}}{R_{36} + R_{34}} = 1/2 \times \frac{K}{K-1}$$

Thus, the selection of the values of the potentiometers 32 and the impedance 30 and the values of the potentiometer 36 and the impedance 34 should be large enough not to excessively load the pilot generators 26 and 28, but low enough such that the pattern field resistor 40 is large by comparison.

The actual pull on the strip by the winding reel 22 may be expressed for the purpose of one example only as follows:

$$\text{One H.P.} = \frac{(\text{speed}) \text{ tension}}{33,000} = EI = 746 \text{ watts}$$

For a 100 lb. initial tension, and 50% taper application, with $I=10$ amps as regulated by the voltage source 71, in accordance with desired initial tension, and a speed of 330 ft./mm.

$$\text{H.P.} = \frac{330(100)}{33,000} = 1 \text{ H.P.} = (10 \text{ amps}) 74.6 \text{ volts}$$

for minimum coil diameter.

At maximum coil diameter

$$\text{H.P.} = \frac{330(50)}{33,000} = 0.5 \text{ H.P.} = (10 \text{ amps}) (37.3 \text{ volts})$$

Thus, the reduction in strip tension is accomplished by a reduction in the voltage applied to the reel motor 24.

Although the present invention has been described with a certain degree of particularity, it should be understood that the present disclosure has been made only by way of example and that numerous changes in the details of construction and the combination and arrangement of parts may be resorted to without departing from the scope and the spirit of the present invention.

I claim as my invention:

1. In control apparatus for a strip winding reel operative with a moving strip of material, said reel being operative with a motor for controlling the operating speed of the winding reel, the combination of a first speed sensing device for providing a first control signal that varies as a function of the operating speed of said winding reel, a second speed sensing device for providing a second control signal that varies as a function of the movement speed of said strip, a motor control device responsive to said first and second control signals and operative with said motor, with said motor control device including a predetermined strip parameter adjusting device operatively connected to each of said first and second sensing devices to adjust the response of said motor control device to each of said first and second control signals respectively in accordance with a predetermined percentage of each of said first and second control signals.

2. In adjustable strip tension control apparatus for a strip winding reel operative with a moving strip of material, said reel being operative with a motor for controlling the operative speed of said winding reel, the combination of a first speed sensing device operative with said winding reel for providing a first control signal having a value that varies in accordance with the operative speed of said winding reel, a second speed sensing device operative with said strip for providing a second control sig-

nal having a value that varies in accordance with the movement speed of said strip, a motor control device responsive to said first and second control signals for controlling the operative speed of said winding reel in accordance with the value of said first and second control signals, and a strip tension adjustment device operative with each of said first and second speed sensing devices for adjusting to a predetermined percentage the value of each of said first and second control signals for providing a predetermined adjustment in the tension of said strip.

3. In tension control apparatus for a strip winding device operative with a moving strip of material, with said winding device including a motor for controlling the operative speed of said winding device, the combination

15 of a first speed sensing device operative with said winding device for providing a first control signal that varies as a function of the operating speed of said winding device, a second speed sensing device operative with said strip for providing a second control signal that varies as a function of the movement speed of said strip, a strip tension control circuit including a first adjustable control member operative with said first speed sensing device for adjusting the value of said first control signal and a second adjustable control member operative with said second speed sensing device for adjusting the value of said second control signal, a motor control device operative with said motor and responsive to the adjusted value of each of said first and second control signals for controlling the operation of said winding device in accordance with a predetermined percentage of each of said first and second control signals as determined by the adjustment of said respective first and second adjustable control members.

4. In strip tension control apparatus for a strip winding reel operative with a moving strip of material, said reel being operative with a motor for controlling the operational speed of the winding reel, the combination of a first speed sensing device operative with said winding reel for providing a first control signal that varies as a function of the operating speed of said winding reel, a second speed sensing device operative with said strip for providing a second control signal that varies as a function of the movement speed of said strip, a pair of series connected impedance devices each having an adjustable contact arm, with one of said impedance devices being connected in series with said first speed sensing device and the other of said impedance devices being connected in series with said second speed sensing device and being operative to provide between said respective contact arms a third control signal, with said respective contact arms being adjustable to provide between said contact arms said third control signal in accordance with a predetermined desired strip tension pattern, and a motor control device operatively connected to said contact arms for responding to said third control signal for controlling the tension of said strip relative to said strip winding reel in accordance with said predetermined desired strip tension pattern.

5. In strip tension control apparatus for a winding reel operative with a moving strip of material, with said reel being operative with a motor for controlling the operation of said winding reel, the combination of a first control signal source operative with said winding reel for providing a first control signal that has a voltage value proportional to the speed of said reel, a second control signal source operative with said strip for providing a second control signal that has a voltage value proportional to the speed of said strip, a control circuit including a first impedance member responsive to said first control signal and a second impedance member responsive to said second control signal, with said first impedance member having a first adjustable output connection and with said second impedance member having a second adjustable output connection for providing between said first and second output connections a third control signal having a value corresponding to a predetermined relationship between said

60 65 70 75

first and second control signals, and a motor control device operatively connected to each of said output connections for controlling the operation of said winding reel and thereby the tension of said strip relative to said winding reel in accordance with the value of said third control signal.

6. In control apparatus for a strip winding reel operative with a moving strip of material, with said winding reel being operative with a motor for controlling the operation of said winding reel relative to said strip, the combination of a first speed sensing device operative with said winding reel for providing a first control signal that varies as a function of the operating speed of said winding reel, a second speed sensing device operative with said strip for providing a second control signal that varies as a function of the movement speed of said strip, and a strip control device operative with said motor and including a first adjustable control member operative with said first speed sensing device for adjusting the value of said first control signal and a second adjustable control member operative with said second sensing device for adjusting the value of said second control signal, with said strip control device being operative to control the operation of said winding reel relative to said strip in accordance with a predetermined combination of said first control signal and said second control signal.

7. In control apparatus for a strip winding reel operative with a moving strip of material, with said winding reel being operative with a motor for controlling the operating speed of said winding reel, the combination of a first speed sensing device operative with said winding reel for providing a first control signal that varies as a function of the operating speed of said winding reel, a second speed sensing device operative with said strip for providing a second control signal that varies as a function of the movement speed of said strip, and a strip tension control device operative with said motor and including a first adjustable control member operative with said first speed sensing device for adjusting the

value of said first control signal and a second adjustable control member operative with said second speed sensing device for adjusting the value of said second control signal, with said strip tension control device being operative to control the operative speed of said winding reel in accordance with the sum of a predetermined portion of said first control signal and a predetermined portion of said second control signal.

8. In a strip control apparatus for a strip winding reel operative with a moving strip of material, said reel being operative with a motor for controlling the tension of said strip relative to said reel by controlling the operational speed of the winding reel, the combination of a first speed sensing device operative with said winding reel for providing a first control signal that varies as a function of the operating speed of said winding reel, a second speed sensing device operative with said strip for providing a second control signal that varies as a function of the movement speed of said strip, and a motor control device for said motor and including a pair of series connected impedance devices each having an adjustable contact arm, with one of said impedance devices being connected in series with said first speed sensing device and the other of said impedance devices being connected in series with said second speed sensing device, with said contact arms being adjustable to provide between said contact arms a third control signal in accordance with a predetermined desired strip tension pattern, with said motor control device being operative to reduce the value of said third control signal and thereby control the speed of said winding reel as a predetermined inverse function of the diameter of strip wound on said winding reel.
